ROSE PLANT

Filed Jan. 30, 1948

Inventor:
R. L. Byrum
By: Robert Cook
Attorneys.

3

This description of a newly opened flower was made from a rose grown in a greenhouse in the month of November, at Richmond, Indiana:

Color.—*Outside petal*—outside surface: Tyrian Rose, Plate XII; inside surface: Rose Color, Plate XII, shaded with Tyrian Rose, Plate XII. *Intermediate petal*—outside: Tyrian Rose, Plate XII; inside surface: Rose Color, Plate XII, shaded with Tyrian Rose, Plate XII. *Inner petal*—outside surface: Tyrian Rose, Plate XII; inside surface: Rose Color, Plate XII, shaded with Tyrian Rose, Plate XII. **10**

This description was made from a rose that **15** was open for three days in a greenhouse in the month of November, at Richmond, Indiana:

Color.—*Outside petal*—outside surface: Rose Color, Plate XII; inside surface: Rose Color, Plate XII, shaded with Tyrian Rose, **20** Plate XII. *Inside petal*—outside surface: Rose Color, Plate XII; inside surface: Rose Color, Plate XII, shaded with Tyrian Rose, Plate XII.

General color effect.—Newly opened flower—**25** Rose Color, Plate XII, shaded with Tyrian Rose, Plate XII. Three days open—Rose Color, Plate XII.

Behavior.—In greenhouse, persist.

Flower longevity.—Cut roses grown in greenhouse kept at living room temperatures—**30** 4 to 5 days in November.

Reproductive organs

Stamens: Many; arranged regularly about pistils.

Filaments: Short; reddish; most with anthers.

Anthers: Small; yellow; all open at once.

Pollen: Moderate; gold.

Pistils: Medium number.

Styles: Uneven; short; thin; bunched.

Stigma: White.

Ovaries: Some protruding from calyx.

Hips: None have developed as yet.

Sepals: Permanent; short; spear-shaped; curled.

Color—inside—Chromium Green, Plate XXXII, overlaid with a white fuzz; outside—Chromium Green, Plate XXXII.

4

Plant

Foliage:

Leaves.—Compound of 5 to 7 leaflets; abundant; medium size; heavy.

Leaflets.—Shape—elliptical with apex acute; margin simply serrate.

Color.—Mature—upper surface: Dark green; under surface: Moderately green. *Young*—upper surface: light bronze red; under surface: light bronze red.

Rachis.—Medium heavy. Upper side—grooved; hairy; under side—smooth; prickly.

Stipules.—Medium long; medium width; with medium long points turning out at an angle of less than 45°.

Disease.—Resistant to mildew and black-spot.

Growth:

Habit.—Upright.

Growth.—Vigorous.

Canes.—Medium heavy.

Branches.—Dull green. *Thorns*—several; medium length; hooked downward; with long, narrow base. *Prickles*—none.

Hairs—none.

Branches.—Dull green. *Thorns*—several; medium length; hooked downward; with long, narrow base. *Prickles*—none.

Hairs—none.

New shoots.—Bronze. *Thorns*—several; medium length; straight.

I claim:

A new and distinct variety of rose plant characterized as to novelty by the color of the flowers and uniformity of such coloring; the penetrating fragrance of said flowers; the habit of free breaking from any eye as compared with other varieties of the Briarcliff family; and the slow development of the flowers from bud to full blown stages, substantially as shown and described.
